UNITED STATES PATENT OFFICE.

CARL E. PEARSON, OF LANSING, MICHIGAN.

IGNITING APPARATUS.

1,420,340.

Specification of Letters Patent. Patented June 20, 1922.

Application filed August 27, 1917. Serial No. 188,363.

To all whom it may concern:

Be it known that I, CARL E. PEARSON, a citizen of the United States, residing at Lansing, county of Ingham, State of Michigan, have invented a certain new and useful Improvement in Igniting Apparatus, and declare the following to be a full, clear, and exact description of the same, such as will enable others skilled in the art to which it pertains to make and use the same, reference being had to the accompanying drawings, which form a part of this specification.

My invention relates to igniting apparatus and an object of my improvements is to provide an improved apparatus for producing the spark for igniting the charge in internal combustion engines, both in starting and at high speeds.

I secure this object in the apparatus illustrated in the accompanying drawings, in which—

Figure 1 is a plan view, diagrammatic in character, showing an apparatus embodying my invention.

Figure 2 is a detail plan-view of the armature and connecting parts.

c c is an electro-magnet having pole-pieces *c*² and *c*³. *a* is a primary coil and *b* a secondary coil. These coils are wound upon the magnet *c c*. *d* is a rotating armature having the pole-pieces *d*² and *d*³. The armature *d* is adapted to rotate with its bearing shaft *g*, between the poles *c*² and *c*³ of the magnet *c*, its pole-pieces *d*² and *d*³ being adapted to pass closely adjacent of the said pole-pieces as in the usual construction. *e* is an energizing coil wound upon the armature *d*. *e*² and *e*³ are the leads through which the ends of the coils *e* are carried out from the magnet. These leads are joined respectively to the rings *e*⁴ and *e*⁵. *e*⁶ and *e*⁷ are brushes making contact with the rings *e*⁵ and *e*⁴.

f is a battery, or source of electrical current, having the binding posts *f*² and *f*³. There is a conductor wire *f*⁴ connected with the binding post *f*³ and with the brush *e*⁶. There is a conductor wire *f*⁵ leading from the binding post *f*² to a switch *k* through

which it may be connected to the brush *e*⁷. 50

n is a conductor wire leading from the binding post *f*³ to the switch *k* through which switch it may be connected through the conductor *a*² with the primary winding *a* upon the magnet *c*. The primary winding 55

a is continued in the conductor *a*³ and connected with a make-and-break device *h*.

m is a conductor connected with the conductor *n* and with the make-and-break device *h* on the opposite side of the gap to 60 that at which the conductor *a*³ is connected.

i is a condenser connected across the gap in the make-and-break device *h*.

The secondary coil *b* is continued in a conductor *b*² and is joined to a distributor *j* by which the current is conveyed to the different cylinders. This latter is a conventional construction and needs no further description. 65

The switch *k* may be turned to the position shown in dotted lines in which position the connection will be made from the battery *f* through the primary coil *a* and the interrupter *h* in the usual manner. The 70 switch is turned to this position to start the engine.

As soon as the engine has attained a running speed the switch *k* is turned to the position shown in full lines in which the battery *f* is connected through the coil *e* and the current flows steadily through said coil maintaining the magnetism of the armature *d*. The rotation of the armature *d* changes the direction and intensity of the magnetic flux through the magnet *c*. This variation in the magnetic flux sets up a current in the primary coil *a* which current is broken at the proper time relative to the rotation of the armature *d* by the make-and-break device *h*. Thus causing a high potential induced current in the secondary *b*². 75 80 85

By the above construction the apparatus consisting of the parts *c d* acts as a dynamo to produce a spark at high speeds and as a sparking coil energizes in the usual way through the battery at slow speeds and at 90 starting the engine. 95

What I claim is:
In an ignition system for internal com-

bustion engines, the combination of a dynamo having a field magnet with a soft iron core, an armature with a soft iron core adapted to rotate between the poles of the 5 field magnet, the field magnet being wound to constitute a sparking coil, the armature core being wound with an energizing coil, a make-and-break device in circuit with

windings on the field magnet, a battery and means for throwing said battery in circuit 10 with said make-and-break-device and the windings in the field magnet, or in circuit with said energizing coil.

In testimony whereof, I sign this specification.

CARL E. PEARSON.
